MOTOR COMPRESSOR

Raul Pateras Pescara, Paris, France

Application January 5, 1933, Serial No. 650,348
In France July 5, 1932

5 Claims. (Cl. 230—56)

The present invention relates to motor compressors of the type in which two opposed motor pistons are actuated directly by the internal combustion of a fuel.

5 In machines of that type, the inner ends of the pistons reciprocate in a motor cylinder into which the fuel is injected and in which it is subsequently ignited, the whole working on the two stroke principle. The outer ends of the pistons reciprocate in a fluidtight manner in two compression cylinders respectively disposed on either side of said motor cylinder and coaxially therewith. The return stroke of the pistons is caused by the expansion of the air cushions that remain 10 in the clearance spaces of said cylinders at the end of the outstroke.

The chief object of the present invention is to provide a motor compressor of that type in which there is no risk of leakage through the inlet valves of the compression cylinders during the 20 period of time for which there are high pressures in said cylinders.

According to my invention, I obtain this result by disposing the inlet valves in a chamber placed laterally with respect to the compression cylinders and communicating therewith through a port that is covered by the piston during the 25 periods of the compression and expansion strokes for which the pressure in the compression cylinder is very high.

Another object of my invention is to provide a compressor of the type above referred to in which air is allowed to enter into the compression cylinder during the instroke thereof as soon as 30 the pressure in said cylinder has fallen back to the atmospheric pressure, in spite of the above described arrangement of the inlet valves.

According to my invention, I obtain this result by providing in each compression piston a 35 conduit connecting the outer face thereof with a point of its cylindrical wall, said conduit being provided with a supplementary inlet valve.

These and other objects of the present invention will be better understood from the following 40 description of a preferred embodiment of my invention, with reference to the accompanying drawings, given merely by way of example, and in which:

Fig. 1 is an elevational view, partly in section, 45 of a motor compressor according to the present invention;

Fig. 2 is a horizontal axial section of said motor compressor;

Fig. 3 is a composite view the right hand side 50 of which is a section on the line AB of Fig. 1

and the left hand side of which is a section on the line CD of Fig. 1;

Fig. 4 is a diagram illustrating the operation of the compressor;

Fig. 5 shows another embodiment of the pistons including an auxiliary inlet valve;

Fig. 6 shows a complete compressor unit in elevation with parts broken away.

In the embodiment shown in the drawings, all the stationary parts of the motor compressor 10 form a unit 1 which comprises:

(a) three cylinders (compression cylinder 101 provided with longitudinal slots 11 and connected with delivery pipe 105 through outlet valves not shown in the drawings, motor cylinder 102, the 15 ends of which are provided with cooling fins 24 and with a piece 25 screwed thereon and fitted with packing rings 26, and a second compression cylinder, similar to cylinder 101 and not shown in the drawings);

(b) a chamber 21 carried by each compression cylinder, connected with the atmosphere through openings 20 provided with air inlet valves 19, and connected with the inside of the compression cylinder through a port 22;

(c) a casing 104 inclosing a chamber 12 extending along the whole length of the compressor and connected with motor cylinder 102 through ports 14;

(d) a chamber 15 carried by each compression cylinder 101, connected with the inside of said cylinder through ports 30 and with chamber 12 through ports 16 provided with valves 17;

(e) two longitudinal external recesses 8 provided on opposite sides of said casing 104, closed on the outer side by plates 9, and connected with chamber 15 through ports 18; said recesses are disposed along groove 11 of compression cylinder 101.

Two pistons such as 2 are fitted in said cylinders in such manner that their outer ends reciprocate in the compression cylinders respectively and their inner ends (of reduced section) reciprocate in motor cylinder 102. The inner faces of the enlarged ends of the pistons are 45 provided with an annular recess 27 for receiving the end of the motor cylinder.

The pistons are connected together through rods 3 pivoted at one end about journals 4 provided on the pistons, and at the other end to 50 cranks 5 pivoted about journals 6 fitted in unit 1.

Journals 4 also carry sliding members 7 adapted to reciprocate in a piston like manner in guiding recesses 8. The inner face of said sliding members is provided with a plate 10 adapted to 55

cover the portion of groove 11 located between said journal 4 and the inner end of said groove.

The operation of the apparatus will be better understood by referring to the diagram of Fig. 4 in which the pressures in one of the compression chambers are plotted in ordinates and the displacements of the corresponding piston are plotted in abscissas.

The piston starts from its innermost position corresponding to point M of the diagram. It compresses air until it reaches a position corresponding to point N of the diagram, for which valves 17 open, thus connecting scavenging air reservoir 12 with compression cylinder 101 through ports 30, chamber 15, and ports 16. From N to O the piston drives compressed air into the scavenging air reservoir. When the piston reaches a position corresponding to point O, it closes ports 11 and 30 so that there is no longer any communication between the compression cylinder and chamber 15. From O to P, piston 2 compresses air into the compression cylinder 101. At point K, that is when the pressure in cylinder 101 begins to be very high, piston 2 covers port 22 so that there is no longer any connection between cylinder 101 and chamber 21. When piston 2 reaches a position corresponding to point P, the outlet valves (not shown in the drawings) open and from P to Q air is delivered into outlet pipe 105 at a constant pressure. When piston 2 is in a position corresponding to point Q, said outlet valves are closed. From Q to R, at the beginning of the instroke, the cushion of compressed air remaining in the clearance space of the cylinder expands down to the atmospheric pressure. When piston 2 reaches a position corresponding to point R, it uncovers port 22 and inlet valves 19 open. From R to M the air from the outside enters into the compression cylinders through said inlet valves and ports 22.

During the whole of the outstroke of piston 2 small pistons 7 compress air into chambers 8, which are always in communication with the scavenging air reservoir 12 through ports 18 and 16, said pistons 7 continuing to act even when pistons 2 have covered ports 11.

During the period of time for which ports 22 are covered by pistons 2 (from point K to point R of the diagram), any connection between the inside of cylinder 101 and ports 20 is cut off so that no leakage of compressed air can take place through valves 19. This is a very important result in view of the high pressure existing inside cylinder 101.

When the compressor works with its maximum power, the outstroke goes as far as Q' (Fig. 4) and the expansion of the cushions of compressed air remaining in the clearance space of the cylinder takes place as far as R', below atmospheric pressure since the connection of the inside of cylinder 101 with chamber 21 is established only when piston 2 uncovers port 22. It is desirable to recover the lost work corresponding to the cross-hatched portion of the diagram.

Such a result can be obtained with an arrangement such as shown in Fig. 5.

According to that arrangement, piston 2 is provided with a conduit 33, 34 connecting the outer face of the piston to an intermediate point of the cylindrical wall thereof. Said conduit is provided with a valve 31 subjected to the action of a spring 32 of relatively small strength. The point at which conduit 34 opens into the

wall of piston 2 is so chosen that when the pressure in cylinder 101 passes below the atmospheric pressure, conduit 34 is located opposite port 22, so that valve 31 opens and air can enter into cylinder 101.

Such an arrangement has the further advantage that the compressed air present in chamber 21 during the beginning of the instroke expands, through conduit 34 and valve 31, into cylinder 101 as soon as the pressure in cylinder 101 during the instroke of piston 2 becomes lower than the pressure in chamber 21 so that, when ports 22 are uncovered by piston 2 the air in chamber 21 is already expanded and valve 19 opens much more quickly. The air compressed in chamber 21 at a pressure corresponding to point K of the diagram of Fig. 4 expands into cylinder 101 during the part I—R of the instroke.

Plates 10 serve to prevent the lubricating oil of pistons 7 to mix with the lubricating oil of pistons 2.

While I have described what I deem to be a preferred embodiment of my invention, it should be well understood that I do not wish to be limited thereto as there might be changes made in the arrangement, disposition and form of the parts without departing from the principle of my invention as comprehended within the scope of the appended claims.

What I claim is:

1. In a motor compressor including a motor cylinder, two compression cylinders disposed on opposite sides thereof and coaxially therewith, and two opposed pistons the inner ends of both of which reciprocate in the motor cylinder and the outer ends of which reciprocate in the compression cylinders respectively, the combination of a chamber provided on the outside of each compression cylinder at an intermediate point thereof, said cylinder being provided with a port at said point so as to connect its inside with said chamber, and at least one inlet check valve in said chamber for allowing air from the outside to enter therewith.

2. In a motor compressor including a motor cylinder, two compression cylinders disposed on opposite sides thereof and coaxially therewith, and two opposed pistons the inner ends of both of which reciprocate in the motor cylinder and the outer ends of which reciprocate in the compression cylinders respectively, the combination of a chamber provided on the outside of each compression cylinder at an intermediate point thereof, said cylinder being provided with a port at said point so as to connect its inside with said chamber, at least one inlet check valve in said chamber for allowing air from the outside to enter therewith, each compression piston being provided with a conduit connecting its outer face with an intermediate point of the cylindrical wall thereof so located that communication is provided between said port and said conduit, a check valve provided in said conduit for allowing air to enter therethrough into said cylinder.

3. A device according to claim 2 further comprising a spring of relatively small strength for applying the last mentioned check valve against its seat.

4. In a motor compressor including a motor cylinder, two compression cylinders disposed on opposite sides thereof and coaxially therewith, two opposed pistons the inner ends of both of which reciprocate in the motor cylinder and the outer ends of which reciprocate in the compression cylinders respectively, the combination of a

chamber provided on the outside of each compression cylinder at an intermediate point thereof, said cylinder being provided with a port at said point so as to connect its inside with said chamber, and at least one check valve for allowing air to pass only in one direction through said chamber.

5. In a motor compressor including a motor cylinder having an inlet port, two compression cylinder disposed on opposite sides thereof and coaxially therewith, two opposed pistons the inner ends of both of which reciprocate in the motor

cylinder and the outer ends of which reciprocate in the compression cylinders respectively, the combination of a chamber provided on the outside of each compression cylinder at an intermediate point thereof and communicating with said inlet port, said cylinder being provided with a port at said point so as to connect its inside with said chamber, and at least one check valve for allowing air to pass only in one direction through said chamber towards said port.
